CROWN CAP SPOTTING APPARATUS

Paul E. Pearson, Chicago, Ill., assignor to Continental Can Company, Inc., New York, N. Y., a corporation of New York

Application November 30, 1942, Serial No. 467,397

20 Claims. (Cl. 154—1)

The invention relates generally to apparatus for forming and affixing center spots to container closure caps of the crown type, each such cap including a metallic cup having a skirt adapted to fit over and grip the pouring neck of a can, bottle, or other container and a sealing pad of cork or other suitable yieldable material for engaging said neck and effectively sealing the contents of the container, and said invention primarily seeks to provide certain new and useful improvements over the machine structure disclosed in my U. S. Letters Patent, filed October 28, 1938, No. 2,309,667, issued February 2, 1943, which said improvements are designed to provide complete control of the spots from the time they are formed until they are affixed in proper centered relation in the crown caps and yet assure against gumming up of the forming punches by application of heat to the spot material at or closely adjacent the punches.

Closure caps designed for use on containers for beer or similar beverages usually have the sealing pads thereof faced with an impervious liner disk of aluminum or other foil or treated paper so as to prevent direct contact between the beverage and the pad and also to prevent leakage of gases. It has been found advantageous to employ facing disks of the "center spot" type, that is to say, disks of a diameter less than that of the pad so as to protect the beverage from pad contact and yet permit contact between the container neck and an annulus of pad surface so as to provide the most effective seal possible. The affixing of lining disks to cap pads, particularly disks of the "center spot" type, has presented numerous problems. Probably the most effective manner of affixing the disks has been by use of a heat fusible adhesive, that is to say, an adhesive normally non-tacky but rendered tacky by application of heat. The positioning of the small diameter spots in perfectly centered relation on the pads in the crown caps makes it necessary to maintain complete control of the spots from the moment they are formed throughout the handling thereof including the heating and affixing steps, and the heating of the spots must be accomplished in a manner for assuring against heating of the spot forming punch and die equipments or the spot material at the spot forming station because the application of heat in this region will result in gumming up of the punching equipment and faulty operation and stoppages of the machine. It is the purpose of the invention to provide efficiently operating means for maintaining the desired control of the spots

from the time of their formation to the time of their application to the crown caps and which is designed to assure against objectionable application of heat at the spot forming station.

5 In its more detailed nature the invention seeks to provide, in combination, spot punching means, a transfer rotor having a multiple of spot receiving stations thereon and means at each station for receiving formed spots directly from the 10 punching means and holding the same, means for indexing the transfer rotor, a carrier rotor having a multiple of spot carrier stations thereon and means at each station for receiving spots from the transfer rotor and holding the same, 15 means for indexing the carrier rotor, means disposed remotely from the transfer rotor for heating spots held on the carrier rotor, and means for bringing about engagement of the carrier rotor borne heated spots with crown caps for 20 affixing the spots in centered relation in said caps.

An object of the invention is to provide an apparatus of the character stated in which the spot receiving and holding means on both rotors are 25 in the nature of radially supported cup-like receptacles, and in which means is included for positively stripping the spots from the transfer rotor receiving means and placing them in the carrier rotor receiving means.

30 Another object of the invention is to provide an apparatus of the character stated in which the spot stripping and placing means effective to transfer the spots from the transfer rotor to the carrier rotor includes a stripper plunger axially 35 reciprocable in each cup-like receptacle at each transfer rotor station, and an actuator bar common to the plungers at each said station, and cam actuated means for reciprocating said plungers.

With the above and other objects in view that 40 will hereinafter appear, the nature of the invention will be more fully understood by following the detailed description, the appended claims and the several views illustrated in the accompanying drawings.

45 In the drawings:
Figure 1 is a front elevation of a machine embodying the invention, parts being broken away and in section.

Figure 2 is a fragmentary rear elevation, parts 50 being broken away and in section at the plane of the cam shaft.

Figure 3 is a fragmentary vertical section taken through punch housing and frame bed across the position of the punch slide.

55 Figure 4 is a fragmentary vertical cross sec-

tion through the punching station, the transfer rotor and a portion of the carrier rotor.

Figure 5 is a fragmentary plan view illustrating the carrier rotor, the transfer rotor and a portion of the spot forming means.

Figure 6 is a fragmentary vertical cross section taken on the line 6—6 on Figure 5.

Figure 7 is a fragmentary vertical longitudinal section taken through the axis of the transfer rotor.

Figure 8 is an enlarged fragmentary vertical cross section on the line 8—8 on Figure 5.

Figure 9 is an end elevation of one of the carrier rotor borne spot carrier elements.

Figure 10 is an end elevation of one of the transfer rotor borne spot carrier elements.

The present invention relates principally to certain new and useful improvements in the particular form of crown cap spotting machine disclosed in my U. S. Letters Patent, No. 2,309,667 issued February 2, 1943, the improvements residing in a novel arrangement of spot carrier rotor, transfer rotor and punching equipment desired to assume punch control of the spots from the time of their formation to the time of their application, and to prevent gumming up of the punching equipment by application of heat. Since the portions of the machine other than those just referred to are disclosed in detail in the earlier filed application they will be described herein only briefly.

In the example of embodiment of the invention herein disclosed, the machine includes a bed structure 5 mounted on supporting legs 6. A drive motor 7 is provided and drives the power shaft 8 through suitable pulley and belt connections 9. The shaft 8 in turn drives the main cam shaft 10 through worm and wheel connections 11, and the shaft 10 is equipped with an indexing cam 12 which engages station rollers 13 projecting from the drive disk 14 secured upon the carrier rotor shaft 15 and serves to index the shaft 15 and the rotor fixed thereon station-by-station in the manner well-known in the art.

As in the machine disclosed in the previously filed application a carrier rotor 16 which is secured on the rotor shaft 15 is provided with eight faces or stations and is indexed about a horizontal axis. From each of the eight faces of the rotor projects a row of five equidistantly spaced spot carrying elements generally designated 17. These elements all extend like distances from the respective rotor face and provide cup-like receptacles for receiving and holding formed spots.

Each of the rotor supported carrier elements generally designated 17 comprises a shank member 18 having a reduced, externally threaded stem portion 19 which is removably receivable in an internally threaded bore 20 provided in the rotor 16. Each shank member is equipped with an enlarged presser head portion 21 which provides an inwardly directed abutment shoulder 22. A cylindrical casing 23 is pin secured as at 24 on each shank 18 and is cored out to provide a spring chamber 25, and each said casing is mounted in and projects radially from a counterbore 26 in the carrier rotor 16. A cylindriform spot holding and centering sleeve 27 is radially slidable in each casing 23, and a compression spring surrounds a reduced inner portion of the sleeve and engages at its respective ends with the casing 23 and with a shoulder on the sleeve for constantly urging the sleeve in the outward direction, the outward movement of the sleeve be-

ing limited by contact of a shoulder 28 thereof with the shank shoulder 22 previously referred to. It will be observed that the outer extremity of the shank head 21 does not extend out to the end of the sleeve 27 and thus cooperates with the sleeve in providing a cup-like receptacle for holding spots.

In order to facilitate attachment and holding of the spots within the outer end of each sleeve 27 each sleeve has its inner face recessed as at 30 to provide sockets 31 for receiving inserts 32 and their mounting lugs 33, said inserts being shaped to provide gripping ribs 34 for engaging and frictionally retaining edge portions of formed spots deposited within the end extremity of the respective sleeve 27. If desired, the outer end of each sleeve may also be provided with suction relief notches 35.

As in the machine structure disclosed in the earlier filed application, the web of foil, coated at one face with a heat fusible adhesive, is fed from a supply roll 36 over a take-up or feed roll 37. In passing from one roll to the other the web 38 passes over guide rolls 39 and a spring urged tightener roll 40, and the direction of feed is diagonally, laterally, and upwardly in the manner clearly illustrated in Figures 1 and 3 in the drawings. A splined end extension 41 of the cam shaft 10 extends into a spline sleeve 42 rotatably supported within the punch mechanism housing 43, said housing being adjustably slidably mounted as at 44 on the frame bed 5. The sleeve 42 drives the shaft 45 forming a part of an intermittent feed mechanism (not shown) designed to feed the foil web through a helical gear couple 46, and this sleeve also drives a cross shaft 47 through the bevel gear couple 48.

A punch slide 49 is slidably supported as at 50 on the punch mechanism housing 43 and is connected by a pitman 51 with an eccentric 52 secured on the cross shaft 47. It will be obvious that as the shaft 47 is rotated a reciprocatory movement will be imparted to the slide 49. The slide is provided with spaced cross bars 53 which serve to support a battery of five punch units, and the cross bars also are equipped with bores for frictionally receiving two side rods 54 which have limited lost motion connection as at 55 in a bracket 56 fixedly supported on the housing. An adjustable stop screw 57 is carried by the bracket 56 and is engageable with the upper end of a rocker member 58 pivotally supported as at 59 on one of the slide cross bars 53. The punch members carried by this slide are designated 60 and are removably mounted as at 61 on the cross bar 53 nearest to the carrier rotor.

The punch members 60 operate through punch bores 62 in a punch block 63 carried by the rods 54, and a die plate 64 is affixed to the punch block. A suitable diagonally disposed slotway is disposed between the opposing faces of the block 63 and die plate 64 for positioning the foil web 38 so that the battery of five punch members 60 may pass through the web and simultaneously punch five spots therefrom. It should be understood that the punch members engage the web at the foil side and not at the heat fusible adhesive bearing face thereof.

The punch elements 60 have axial bores therethrough and each bore mounts a reciprocable stripper rod 65. Each stripper rod 65 is equipped with a stripper head 66 which is normally retracted within the end extremity of the respective punch member 60 by a compression spring 67 which engages at one end with the removably

mounted punch member and at its other end with an abutment head 68 secured upon the rod 65 within a bore 69 in the cross bar 53 which carries the punch members. Adjustable tappets 70 are slideable in bores 71 provided therefor in the other cross bar 53 and engage at their ends with the stripper rods 65. The tappets 70 are engaged by the lower end of the rocker member 58 in the manner clearly illustrated in Figure 4.

It will be apparent that each time the slide 48 is advanced the punch members 60 will pass through the web 38 and simultaneously form five spots. Just after the spots are thus formed by the punches the upper end of the rocker 58 will engage the stop screw 57 and rocking movement thus imparted to the rocker will cause the tappets 70 to be advanced, and this advancement of the tappets will impart movement to the stripper rods 65 and cause the heads 68 to strip the formed spots from the punch members for a purpose that will later become apparent.

Between the carrier rotor 16 and the spot forming punch equipment, and parallel the axis of the horizontal rotor is mounted a transfer rotor shaft 72. This shaft is supported in a stationary bracket 73 secured to the machine framing, being mounted in anti-friction bearings 74 supported by the bracket. A spur driver gear 75 is secured on the shaft 72, being adjustably mounted as at 76 so that a measure of adjustment of the gear with relation to the shaft on which it is mounted can be effected.

The bracket 73 also supports bearings 77 for a rock shaft 78 which is disposed in spaced parallel relation to the rotor shaft 72. Two plate cams 79 are fixedly secured on the bracket as at 80 and each is provided with a circular face groove 81 disposed concentrically with relation to the axis of the shaft 72, said grooves being disposed in opposed relation. Each plate cam 79 includes a displaceable sector 82 which includes a portion of the respective plate groove, and the sectors are secured to arms 83 adjustably mounted as at 84 on and projecting from the rock shaft 78 so that as the shaft is rocked the sectors will be moved outwardly, to displace the sector grooves from aligning relation with the remainder of the grooves in the plate cams, and then again inwardly to restore the sectors and again render complete the circular grooves. An actuator crank 85 is secured on the shaft 78, and this crank is connected by a pitman rod 86 with an actuating means which will be described hereinafter.

The indexing movement of the carrier rotor 16 is applied in the manner hereinbefore described, is transmitted to the transfer rotor shaft 72 through a spur gear 87 mounted on the carrier rotor and a meshing intermediate gear 88 supported as at 89 on the bracket 73 and in turn meshing with the driver spur gear 75 which is adjustably secured on the transfer rotor shaft 72.

A transfer rotor 90 is fixed to the shaft 72 and is provided with four stations or faces, it being understood that the driving connections between the transfer rotor and the carrier rotor are such that the faces thereof will be brought into opposition or perfect registry at each step movement of the carrier rotor.

In each face of the transfer rotor there is provided a radial slot 91 covered by a plate 92 which is removably mounted on the rotor face as at 93. A bar 94 is mounted in each slot 91 and is equipped at each end with a roller 95 which projects beyond the end of the transfer roller and into one of the cam plate grooves 81. It will be

observed by reference to Figures 5 and 6 of the drawings that each cam plate 79 is provided with a removable, groove defining wall portion or segment 96, and by removal of these segments and the cover plates 92, the bars 94 may be removed from the transfer rotor slots.

A battery of five plungers 97 project through bores in each bar 94, inward movement of the plungers relative to the respective bar 94 being prevented by shoulders 98, and outward movement of the plungers relative to the respective bar being prevented by a keeper plate 99 which engages the inner face of the bar and extends into recesses 100 formed in the plungers. At their inner ends the plungers extend into recesses 101 formed in the transfer rotor shaft 72, and at their outer ends the plungers carry ejector heads 102. The ejector head 102 of each plunger 97 is recessed within a cup-like spot receiver 103 which is carried at the outer end of a sleeve 104 slidably surrounding the plunger within a bore 105 formed in the plate 92. Spaced inwardly from the plate 92, each sleeve 104 is equipped with an abutment ring 106 designed to limit outward movement of the plungers 97 and receivers 103 relative to said plate. A compression spring 107 is interposed between each abutment ring 106 and the opposing face of the respective bar 94 and serves to cause the plungers 97 and receivers 103 to move outwardly together until the abutment rings 106 engage the respective plate 92, and then permit the plungers to move outwardly an additional distance relative to the receivers 103 so that the ejector heads 102 can displace spots which have been attached to and held in the receivers.

The receivers 103 are provided with spot attaching or holding means of the same nature as those previously described in connection with the carrier rotor. For this purpose each cup-like receiver 103 has its inner face recessed as at 108 to provide sockets 108 for receiving inserts 110 and their mounting lugs 111 so formed as to provide spot gripping ribs 112 which engage and frictionally hold edge portions of spots deposited in the receiver 103 in the manner previously described.

From the foregoing description it will be apparent that the transfer rotor and the carrier rotor are indexed in timed relation so that if the one row of receivers 103 on the transfer rotor is presented in registry with the punch openings in the die plate 84 of the punching equipment, the diametrically oppositely disposed row of receivers 103 will be disposed in perfect registry with a row of receivers on the carrier rotor. Each time this alignment of punches and receivers occur a complement of spots will be punched and deposited in the receivers 103 registering with the punch openings and at the same time the cam plate sectors 82 will be displaced by a rocking of the shaft 78 to project the bar 94 then in engagement with the sectors outwardly thereby causing the plunger and receiver complement 97, 103 of that bar to move outwardly in unison to first place the receivers against or in very close registering proximity to the then aligned row of receivers 27 on the carrier rotor 16, and then additionally project the plungers 97 so that the heads 102 thereof will transfer the spots from the receivers 103 of the transfer rotor into the receivers 27 of the carrier rotor. Before any movement is imparted to the transfer rotor the plate sectors 82 are replaced by reverse rocking movement of the shaft 78, and the means for rocking this

shaft in proper timed relation to the indexing of the rotors will be described hereinafter.

A heating equipment in the form of gas burners 113 is disposed above the carrier rotor 16 so as to directly apply heat to the spots which are held by the receivers 27 on that rotor as they are presented upwardly at the heating station as illustrated in Figure 1 of the drawings. Since the punches engage the foil web at the face thereof of which is not coated the spots are deposited in the receivers 103 of the transfer rotor with the adhesive thereon directed inwardly, and are transferred into the receivers 27 of the carrier rotor 16 with the adhesive thereon directed outwardly so as to facilitate direct heating of the adhesive at the heating station. The heating means 113 is supported on an arm 114 which is pivotally mounted as at 115 so that the heating means can be moved away from the carrier rotor 16 whenever desired.

A crown cap feeding chute 116 is disposed vertically in tangential relation to the path of travel of the receiving ends of the carrier rotor receivers 27 in position for placing successive rows of crown caps so that the end extremities of the receivers 27 approaching the spot affixing station which is diametrically oppositely disposed with relation to the station at which the receivers 27 receive the spots will enter the crown caps and deposit the now tacky spots therein in the manner clearly described in the previously filed application hereinbefore referred to.

The spots thus applied are pressed by a reciprocable presser segment 117 mounted on a slide 118 having rack and gear connection as at 119 with a horizontally disposed rock shaft 120. Rocking movement is applied to the shaft 120 by a crank and roller connection as at 121 with an actuator cam 122 secured upon the cam shaft 10. Each time the presser segment 117 is advanced it presses the crown caps against the ends of the shank presser heads 21 aligned with the segment so as to assure firm attachment of the spots with the crown cap pads.

The rock shaft 120 is provided with an eccentric 123 which turns in an opening provided therefor in an actuator arm 124 fulcrumed at its lower end as at 125 on a fixed support and adjustably connected at its upper end with the thrust rod 86 for imparting movement to the plate cam sector arms 83 in the manner hereinbefore described.

It will be observed by reference to Figure 1 of the drawings that as the carrier elements on the carrier rotor approach the bottom or crown cap discharging station, the spotted crown caps on the ends thereof engage stripper fingers 126 which strip them from the elements and cause them to fall onto a take-off conveyor 127 by which they are conveyed out of the machine.

It is of course to be understood that the details of structure and the arrangement of parts may be variously changed and modified without departing from the spirit and scope of the invention.

I claim:

1. In a crown cap and spot assembling machine having a spot forming station, means for supporting heat fusible adhesive coated material at the spot forming station, spot punching means at the spot forming station for punching spots from the heat fusible adhesive coated material, a multi-faced transfer rotor, a multi-faced carrier rotor, means for indexing the rotors about horizontal axes, cup-like spot receivers project-

ing radially in groups from the faces of both rotors, means for forcing spots formed by the punching means directly into receivers on the transfer rotor to be held and carried therein, means for forcing spots from the receivers on the transfer rotor into receivers on the carrier rotor to be held and carried therein, means for directly heating the spots while being carried by the carrier rotor and at a point remote from the punching station, said machine also having a spot and crown cap assembling station, and means for bringing the spots and crown caps into contacting relation at the assembling station for uniting the spots held and heated on the carrier rotor with the crown caps by affixing the adhesively coated face of the spots against the crown caps.

2. In a machine of the character described, a generally cylindriform rotor rotatable about a fixed axis, rows of cup-like spot receiving elements disposed in equidistantly spaced relation about the circumference of the rotor, each said row comprising a plurality of said elements all extending like distances from the rotor with their axes projected radially in a common plane and in parallel equidistantly spaced relation, means for indexing the rotor to present the element rows at successive stations including a spot forming station and a spot delivering station, means reciprocably mounted in fixed position at the spot forming station for forming spots and depositing them in the successively presented receiving element rows, spot ejecting plungers in the elements of each row, and means for actuating the plungers successively presented at the delivering station for ejecting the spots from the elements at that station.

3. In a machine of the character described, a generally cylindriform rotor rotatable about a fixed axis, rows of cup-like spot receiving elements disposed in equidistantly spaced relation about the circumference of the rotor, each said row comprising a plurality of said elements all extending like distances from the rotor with their axes projected radially in a common plane and in parallel equidistantly spaced relation, means for indexing the rotor to present the element rows at successive stations including a spot forming station and a spot delivering station, means reciprocably mounted in fixed position at the spot forming station for forming spots and depositing them in the successively presented receiving element rows, spot ejecting plungers in the elements of each row, a bar connecting the plungers in each element row for movement together, and means for moving each bar presented at the delivering station radially outwardly to cause the connected plungers to eject spots from the elements presented at the delivering station.

4. In a machine of the character described, a generally cylindriform rotor rotatable about a fixed axis, rows of cup-like spot receiving elements disposed in equidistantly spaced relation about the circumference of the rotor, each said row comprising a plurality of said elements all extending like distances from the rotor with their axes projected radially in a common plane and in parallel equidistantly spaced relation, means for indexing the rotor to present the element rows at successive stations including a spot forming station and a spot delivering station, means reciprocably mounted in fixed position at the spot forming station for forming spots and depositing them in the successively presented receiving element rows, spot ejecting plungers in the elements

of each row, a bar connecting the plungers in each element row for movement together, each said bar having a roller projecting beyond each end thereof and beyond the end of the rotor, and means engageable with the rollers of each bar at the delivery station for moving the connected bar to cause the connected plungers to move outwardly and eject spots from the elements presented at the delivery station.

5. In a machine of the character described, a generally cylindriform rotor rotatable about a fixed axis, rows of cup-like spot receiving elements disposed in equidistantly spaced relation about the circumference of the rotor, each said row comprising a plurality of said elements all extending like distances from the rotor with their axes projected radially in a common plane and in parallel equidistantly spaced relation, means for indexing the rotor to present the element rows at successive stations including a spot forming station and a spot delivering station, means at the spot forming station for forming spots and depositing them in the successively presented receiving element rows, spot ejecting plungers in the elements of each row, a bar connecting the plungers in each element row for movement together, each said bar having a roller projecting beyond each end thereof and beyond the end of the rotor, a plate cam stationarily mounted at each end of the rotor and having a bar roller receiving groove in the face thereof opposing the rotor and arranged concentrically to the rotor axis, each said plate including a displaceable sector disposed at the delivering station and including a portion of the groove, and means for displacing the plate sectors outwardly each time a bar comes to rest at the delivering station to move the connected plungers outwardly and eject spots from the elements presented at the delivery station.

6. In a machine of the character described, a generally cylindriform rotor rotatable about a fixed axis, rows of cup-like spot receiving elements disposed in equidistantly spaced relation about the circumference of the rotor, each said row comprising a plurality of said elements all extending like distances from the rotor with their axes projected radially in a common plane and in parallel equidistantly spaced relation, means for indexing the rotor to present the element rows at successive stations including a spot forming station and a spot delivering station, means at the spot forming station for forming spots and depositing them in the successively presented receiving element rows, spot ejecting plungers in the elements of each row, a bar connecting the plungers in each element row for movement together, each said bar having a roller projecting beyond each end thereof and beyond the end of the rotor, a plate cam stationarily mounted at each end of the rotor and having a bar roller receiving groove in the face thereof opposing the rotor and arranged concentrically to the rotor axis, each said plate including a displaceable sector disposed at the delivering station and including a portion of the groove, and means for displacing the plate sectors outwardly each time a bar comes to rest at the delivering station to move the connected plungers outwardly and eject spots from the elements presented at the delivery station, each said plate also including a marginal groove defining wall portion removably mounted so as to permit radial withdrawal of the bars and the connected plungers.

7. In a machine of the character described, a

generally cylindriform rotor rotatable about a fixed axis, rows of cup-like spot receiving elements disposed in equidistantly spaced relation about the circumference of the rotor, each said row comprising a plurality of said elements all extending like distances from the rotor with their axes projected radially in a common plane and in parallel equidistantly spaced relation, means for indexing the rotor to present the element rows at successive stations including a spot forming station and a spot delivering station, means at the spot forming station for forming spots and depositing them in the successively presented receiving element rows, spot ejecting plungers in the elements of each row, a second rotor arranged parallel the first and having similarly extended rows of cup-like receiving elements and indexed in timed relation with the first rotor to cause the respective rows of receiving elements of the rotors to register at the delivering station and to successively present the elements of the second rotor at the delivering station and at other stations including a heating station and a spot applying station, and means for actuating the plungers presented at the delivering station to displace spots from the respective elements of the first rotor and deposit them in the registering elements of the second rotor.

8. In a machine of the character described, a generally cylindriform rotor rotatable about a fixed axis, rows of cup-like spot receiving elements disposed in equidistantly spaced relation about the circumference of the rotor, each said row comprising a plurality of said elements all extending like distances from the rotor with their axes projected radially in a common plane and in parallel equidistantly spaced relation, means for indexing the rotor to present the element rows at successive stations including a spot forming station and a spot delivering station, means at the spot forming station for forming spots and depositing them in the successively presented receiving element rows, spot ejecting plungers in the elements of each row, a bar connecting the plungers in each element row for movement together, each said bar having a roller projecting beyond each end thereof and beyond the end of the rotor, a plate cam stationarily mounted at each end of the rotor and having a bar roller receiving groove in the face thereof opposing the rotor and arranged concentrically to the rotor axis, each said plate including a displaceable sector disposed at the delivering station and including a portion of the groove, a second rotor arranged parallel the first and having similarly extended rows of cup-like receiving elements and indexed in timed relation with the first rotor to cause the respective rows of receiving elements of the rotors to register at the delivering station and to successively present the elements of the second rotor at the delivering station and at other stations including a heating station and a spot applying station, and means for displacing the plate sectors outwardly each time a bar comes to rest at the delivering station to move the connected plungers outwardly to eject spots from the respective elements of the first rotor and deposit them in the registering elements of the second rotor.

9. In a machine of the character described, a generally cylindriform rotor rotatable about a fixed axis, rows of cup-like spot receiving elements disposed in equidistantly spaced relation about the circumference of the rotor, each said row comprising a plurality of said elements all

extending like distances from the rotor with their axes projected radially in a common plane and in parallel equidistantly spaced relation, means for indexing the rotor to present the element rows at successive stations including a spot forming station and a spot delivering station, means at the spot forming station for forming spots and depositing them in the successively presented receiving element rows, spot ejecting plungers in the elements of each row, a second rotor arranged parallel the first and having similarly extended rows of cup-like receiving elements and indexed in timed relation with the first rotor to cause the respective rows of receiving elements of the rotors to register at the delivering station and to successively present the elements of the second rotor at the delivering station and at other stations including a heating station and a spot applying station, and means operable each time two rows of elements on said rotors are presented in registry at the delivering station for first moving the elements of the first rotor radially into very close registering proximity to the registering elements of the second rotor and then for moving the particular plunger group radially outwardly to displace spots from the first rotor elements and deposit them in the second rotor elements.

10. In a machine of the character described, a generally cylindriform rotor rotatable about a fixed axis, rows of cup-like spot receiving elements disposed in equidistantly spaced relation about the circumference of the rotor, each said row comprising a plurality of said elements all extending like distances from the rotor with their axes projected radially in a common plane and in parallel equidistantly spaced relation, means for indexing the rotor to present the element rows at successive stations including a spot forming station and a spot delivering station, means at the spot forming station for forming spots and depositing them in the successively presented receiving element rows, spot ejecting plungers in the elements of each row, a second rotor arranged parallel the first and having similarly extended rows of cup-like receiving elements and indexed in timed relation with the first rotor to cause the respective rows of receiving elements of the rotors to register at the delivering station and to successively present the elements of the second rotor at the delivering station and at other stations including a heating station and a spot applying station, means mounting the receiving elements of the first rotor on the plungers thereof for limited radial movement with the plungers, and means for actuating the plungers presented at the delivering station to first move the elements mounted thereon radially outwardly into very close registering proximity to the registering elements of the second rotor and then the plungers alone an additional distance to displace spots from the outwardly moved elements and deposit them in said registering elements.

11. In a machine of the character described comprising a generally cylindriform rotor rotatable about a fixed axis, rows of cup-like spot receiving elements disposed in equidistantly spaced relation about the circumference of the rotor, each said row comprising a plurality of said elements all extending like distances from the rotor with their axes projected radially in a common plane and in parallel equidistantly spaced relation, spot ejecting plungers in the elements of each row, a bar connecting the

plungers in each element row, each said bar having a roller projecting beyond each end thereof and beyond the end of the rotor, means yieldably mounting the receiving elements on the plungers for movement with the plungers, means limiting outward movement of the receiving elements, and means engageable with the rollers of each bar for moving the connected plungers and receiving elements outwardly the distance said elements can move and then the plungers an additional distance relatively to said elements as ejectors.

12. In a machine of the character described comprising a generally cylindriform rotor rotatable about a fixed axis, rows of cup-like spot receiving elements disposed in equidistantly spaced relation about the circumference of the rotor, each said row comprising a plurality of said elements all extending like distances from the rotor with their axes projected radially in a common plane and in parallel equidistantly spaced relation, spot ejecting plungers in the elements of each row, a bar connecting the plungers in each element row, each said bar having a roller projecting beyond each end thereof and beyond the end of the rotor, means yieldably mounting the receiving elements on the plungers for movement with the plungers, means limiting outward movement of the receiving elements, a plate cam stationarily mounted at each end of the rotor and having a bar roller receiving groove in the face thereof opposing the rotor and arranged concentrically to the rotor axis, each said plate including a displaceable sector including a portion of the groove, and means for displacing the sectors outwardly when a pair of rollers are in the sector grooves to move the particular bar and the connected receiving elements outwardly the distance said elements can move and then the plungers an additional distance relatively to said elements as ejectors.

13. In a machine of the character described comprising a generally cylindriform rotor rotatable about a fixed axis, rows of cup-like spot receiving elements disposed in equidistantly spaced relation about the circumference of the rotor, each said row comprising a plurality of said elements all extending like distances from the rotor with their axes projected radially in a common plane and in parallel equidistantly spaced relation, spot ejecting plungers in the elements of each row, a bar connecting the plungers in each element row, each said bar having a roller projecting beyond each end thereof and beyond the end of the rotor, means yieldably mounting the receiving elements on the plungers for movement with the plungers, means limiting outward movement of the receiving elements, a plate cam stationarily mounted at each end of the rotor and having a bar roller receiving groove in the face thereof opposing the rotor and arranged concentrically to the rotor axis, each said plate including a displaceable sector including a portion of the groove, and means for displacing the sectors outwardly when a pair of rollers are in the sector grooves to move the particular bar and the connected receiving elements outwardly the distance said elements can move and then the plungers an additional distance relatively to said elements as ejectors, said sector displacing means including a rock shaft, a shaft rocking crank, and a pair of cranks secured to the shaft and attached to the sectors for imparting movement to the latter.

14. In a pad and spot assembling machine having a spot forming station and a spot and pad assembling station, means at said spot forming station for punch-forming spots from adhesive coated material, a rotary carrier on which the spots are deposited as they are punched, a second rotary carrier, means for transferring the spots from the first mentioned carrier to the second carrier, means for operating the carriers in timed relation, means for directly heating the spots on the second carrier while moving toward the assembling station for rendering the adhesive thereon tacky, said heating means constituting the sole heating means and being arranged adjacent the second carrier only at a point remote from the punch-forming means and the first mentioned carrier, means for presenting pads at the assembling station, and means for bringing the spots and pads into contacting relation at the assembling station for uniting the spots and pads by affixing the adhesive coated faces of the spots to the pads.

15. In a pad and spot assembling machine having a spot forming station and a spot and pad assembling station, means at said spot forming station for punch-forming spots from adhesive coated material with the punch passing through from the non-coated side of said material, a rotary carrier on which the spots are deposited as they are punched with the adhesive coated faces of the spots directed inwardly, a second rotary carrier, means for transferring the spots from the first mentioned carrier to the second carrier with the adhesive coated faces of the spots directed outwardly, means for directly heating the spots on the second carrier while moving toward the assembling station for rendering the adhesive thereon tacky, said heating means constituting the sole heating means and being arranged adjacent the second carrier only at a point remote from the punch-forming means and the first mentioned carrier, means for presenting pads at the assembling station and means for bringing the spots and pads into contacting relation at the assembling station for uniting the spots and pads by affixing the adhesive coated faces of the spots to the pads.

16. In a pad and spot assembling machine having a spot forming station and a spot and pad assembling station, means at said spot forming station for punch-forming spots from adhesive coated material, a rotary carrier on which the spots are deposited as they are punched, a second rotary carrier, means for transferring the spots from the first mentioned carrier to the second carrier, means for operating the carriers in timed relation, means for directly heating the spots on the second carrier while moving toward the assembling station for rendering the adhesive thereon tacky, said heating means constituting the sole heating means and being arranged adjacent the second carrier only at a point remote from the punch-forming means and the first mentioned carrier, means for presenting pads at the assembling station, means for bringing the spots and pads into contacting relation at the assembling station for uniting the spots and pads by affixing the adhesively coated faces of the spots to the pads, and means on each rotary carrier for attaching the spots thereto and holding them thereon so that control of the accurate positioning of the spots is never lost from the time they are punched through their travels on the carriers and completion of their attachment to the pads.

17. In a pad and spot assembling machine having a spot forming station and a spot and pad assembling station, means at said spot forming station for punch-forming spots from adhesive coated material with the punches passing through from the non-coated side of said material, a rotary carrier on which the spots are deposited as they are punched with the adhesive coated faces of the spots directed inwardly, a second rotary carrier, means for transferring the spots from the first mentioned carrier to the second carrier with the adhesive coated faces of the spots directed outwardly, means for operating the carriers in timed relation, means for directly heating the spots on the second carrier while moving toward the assembling station for rendering the adhesive thereon tacky, said heating means constituting the sole heating means and being arranged adjacent the second carrier only at a point remote from the punch-forming means and the first mentioned carrier, means for presenting pads at the assembling station, means for bringing the spots and pads into contacting relation at the assembling station for uniting the spots and pads by affixing the adhesive coated faces of the spots to the pads, and means on each rotary carrier for attaching the spots thereto and holding them thereon so that control of the accurate positioning of the spots is never lost from the time they are punched through their travels on the carriers and completion of their attachment to the pads.

18. In a pad and spot assembling machine having a spot forming station and a spot and pad assembling station, means at said spot forming station for punch-forming spots from adhesive coated material, a rotary carrier on which the spots are deposited as they are punched, a second rotary carrier, means for transferring the spots from the first mentioned carrier to the second carrier, means for operating the carriers in timed relation, means for directly heating the spots on the second carrier while moving toward the assembling station for rendering the adhesive thereon tacky, said heating means constituting the sole heating means and being arranged adjacent the second carrier only at a point remote from the punch-forming means and the first mentioned carrier, means for presenting pads at the assembling station, means for bringing the spots and pads into contacting relation at the assembling station for uniting the spots and pads by affixing the adhesive coated faces of the spots to the pads, and complete circular cup-like means on each rotary carrier for receiving and holding spots delivered thereto.

19. In a pad and spot assembling machine having a spot forming station and a spot and pad assembling station, means at said spot forming station for punch-forming spots from adhesive coated material, a generally cylindrical rotary carrier on which the spots are deposited as they are punched, a second generally cylindrical rotary carrier, means for transferring the spots from the first mentioned carrier to the second carrier, means for directly heating the spots on the second carrier while moving toward the assembling station for rendering the adhesive thereon tacky, said heating means constituting the sole heating means and being arranged adjacent the second carrier only at a point remote from the punch-forming means and the first mentioned carrier, means for presenting pads

at the assembling station, means for bringing the spots and pads into contacting relation at the assembling station for uniting the spots and pads by affixing the adhesive coated faces of the spots to the pads, complete circle cup-like means on and projecting radially from each rotary carrier for receiving and holding spots delivered thereto, and means for causing the rotary carriers to rotate in timed relation so that said transferring means will accurately transfer spots from the first mentioned carrier to the second carrier.

20. In a pad and spot assembling machine having a spot forming station and a spot and pad assembling station, means at said spot forming station for punch-forming spots from adhesive coated material, a rotary carrier on which the spots are deposited as they are punched, a second rotary carrier, means for transferring the spots from the first mentioned carrier to the 20

second carrier, means for operating the carriers in timed relation, means for directly heating the spots on the second carrier while moving toward the assembling station for rendering the adhesive thereon tacky, said heating means constituting the sole heating means and being arranged adjacent the second carrier only at a point remote from the punch forming means and the first mentioned carrier, means for presenting pads at the assembling station, means for bringing the spots and pads into contacting relation at the assembling station for uniting the spots and pads by affixing the adhesive coated faces of the spots to the pads, reciprocable means for applying pressure to spots after they are united with the pads, actuator means for said pressure applying means, and means operated from said actuator means for operating said spot transferring means.

PAUL E. PEARSON.
